 Zurich, Switzerland, a corporation of Switzerland

Application April 13, 1945, Serial No. 588,186
 In Switzerland May 26, 1944

7 Claims. (Cl. 126—109)

1

This invention relates to a gas heater primarily intended for use in a thermal power plant in which at least the greater part of a gaseous working medium, preferably air, describes a closed circuit, being raised to a higher pressure in at least one compressor, then brought to a higher temperature in a heater by an indirect supply of heat from an external source and thereafter expanded in at least one turbine. In power plants of this type it is known to arrange the heating surfaces of the heater in a number of passes and to supply part of the fuel to a combustion chamber situated in front of all heating surfaces and the remaining fuel to at least one further combustion chamber arranged between two of the heating surfaces, and further to return to the heater flue gases which have been branched off at any point beyond the heater.

In such plants the tendency is to obtain a given thermal output with a heating surface which is as small as possible, so that the manufacturing cost of the heater can be reduced to the utmost. This can be realized in the simplest manner by adopting the largest possible difference in temperature between the combustion gases and the working medium to be heated. To realize this it has already been proposed to introduce the fuel into the heater not only at one point but at several points, the latter being effected partly between adjacent heating surfaces. In this case approximately the same temperature can be reached at all points of the heater where fuel is burnt and thus, as desired, a greater average difference in temperature between the combustion gases and the working medium to be heated over a considerable range of the heater.

However, the adoption of a high temperature for the combustion gases is often limited by other requirements. For example in the case of fuels containing ash it is generally required that the temperature of the combustion gases at the inlet to the first heater tube nest be so low that a deposit of liquid ash on the heating surfaces is prevented with certainty. To bring about a reduction in the temperature of the combustion gases in front of the inlet to the heater tube nest it has further been proposed to mix these gases with returned flue gases. But the greater the quantity of flue gas that has to be returned, the greater also is the power consumed by the fan for circulating said portion of flue gas, which has a detrimental effect on the overall efficiency of the plant. To overcome this

2

drawback in a thermal power plant of the kind herein referred to, according to the present invention flue gases are only returned to the combustion chambers arranged in front of all the heating surfaces, this possibility depending upon the fact that in the remaining combustion chambers the gases coming from the preceding heating surfaces are already capable of lowering the temperature of the combustion gases sufficiently to ensure that flue gases need not also be returned to these chambers.

In the accompanying drawing a preferred embodiment of a thermal power plant for carrying out the process according to the present invention is shown by way of example and in a simplified mode of representation, those parts of the plant which constitute essential features of the invention being illustrated on an enlarged scale.

In the heater A illustrated in the figure heat from an external source is supplied to the air, since in conjunction with the illustrated embodiment it is assumed that air is used as working medium. This heater A comprises three combustion chambers 1, 2, 3 and three heating surfaces designed as tube nests 4, 5, 6. The tube nests 4, 5 and 6 are disposed in combustion-gas passes 7, 8 and 9 respectively. The combustion chamber 1 is arranged in front of all tube nests 4, 5 and 6, whilst the combustion chamber 2 is situated between the two nests 4 and 5, which as regards the direction of flow of the flue gases are connected in series, and the combustion chamber 3 is situated between the two nests 5 and 6, which as regards the direction of flow of the flue gases are also connected in series. The combustion chamber 1 is arranged in front of all heating surfaces 4, 5, 6, is situated before the lower part of the first tube nest 4, whilst the combustion chamber 2 is disposed between the upper parts of the two tube nests 4, 5 and the combustion chamber 3 between the lower parts of the tube nests 5 and 6.

The air to be heated in heater A enters through a pipe 10 into tube nest 6 and flows from the latter through a pipe 11 into tube nest 5 and from this through a pipe 12 into tube nest 4, where it is heated to the required final temperature. The air heated in this manner passes through a pipe 13 into a turbine 14, in which it expands, this turbine delivering power to a compressor 15 and a generator 16. The air issuing from turbine 14 passes through a pipe 17 into a heat exchanger 18 where it gives up heat to that part of the air which flows from the compressor 15 through a pipe 19 and this heat

exchanger 18 into the pipe 10 connected to the tube nest 6. The expanded air cooled in the heat exchanger 18 passes through a pipe 20 and cooler 33 into the compressor 15 wherein it is re-compressed to a higher pressure and then forced into said pipe 19.

A portion of the flue gases is branched off behind the heater A at point 21 and returned by a fan 22, which is driven by a motor 23, into the combustion chamber 1. A further portion of the flue gases issuing from the heater A passes into a heat exchanger 24 where it serves for heating the fuel delivered by a fan 25, which has to be supplied to burners 26, 27, 28 of the combustion chambers 1, 2 and 3 respectively. The remaining flue gases pass into a heat exchanger 29 where they are employed for heating the combustion air required for the burners 26, 27, 28 and supplied by a fan 30. The fans 25 and 30 are driven by a motor 31.

Should the heater for the working medium comprise less or more than three heating surfaces connected to one another in series in relation to the direction of flow of the flue gases, then the flue gases are also returned solely to the combustion chamber arranged in front of all heating surfaces.

The invention is particularly suited for application where high velocities for the combustion gases are adopted in the heater for the working medium, i. e. when considerable pressure losses occur during the passage of these gases through the heating surfaces. In such a case it is, on account of the power consumption, desirable if the quantity of flue gas which has to be returned to the combustion chamber of the heater for the working medium can be kept as small as possible.

What is claimed is:

1. In a high temperature gas-heating furnace, the combination of means forming a plurality of combustion chambers; means forming a plurality of combustion-gas passes, one of the latter leading from each of said combustion chambers, the combustion-gas pass from each chamber except the last leading to the next combustion chamber in series; an outlet connection leading from the discharge end of said last combustion-gas pass; a plurality of surface heat exchange units, each of said units being mounted within a corresponding combustion-gas pass; tubular means connecting said units in series; means for circulating gas to be heated through the units so connected; fuel burners directed into the various combustion chambers; a branch conduit leading from said outlet connection to the first combustion chamber; and power driven means for propelling gases through said branch conduit toward said chamber, whereby the heating effect of each fuel burner upon the exchange unit in the succeeding combustion-gas pass is controlled by dilution of its products of combustion with cooler combustion products.

2. The combination defined in claim 1 in which the connection to the exchanger units are such that the gas to be heated flows in counter-flow relation to the products of combustion passing through said combustion-gas passes.

3. The combination defined in claim 1 in which each unit of the heat exchanger is multi-tubular and its tubes extend longitudinally through the corresponding combustion-gas pass.

4. The combination defined in claim 1 in which each unit of the heat exchanger is multi-tubular and arranged with its tubes extending longitudinally through the corresponding combustion-gas pass and the connections are such that the gas to be heated flows through the tubes in counter-flow relation to the products of combustion flowing through said combustion-gas passes.

5. The combination defined in claim 1 in which each unit of the heat exchanger is multi-tubular and arranged with its tubes extending longitudinally through the corresponding combustion-gas pass and wherein the connections between such heat exchangers are external to the means enclosing the combustion chambers and the combustion-gas passes.

6. The combination defined in claim 1 in which the combustion-gas passes are substantially vertical and arranged side by side and the various combustion chambers other than the first are in the form of enlargements interposed in approximately horizontal connections between the ends of adjacent combustion-gas passes.

7. The combination defined in claim 1 in which the combustion-gas passes are substantially vertical and arranged side by side and the various combustion chambers other than the first are in the form of enlargements interposed in approximately horizontal connections between the ends of adjacent combustion-gas passes, the heat exchanger units are multi-tubular and extend each beyond the ends of the pass in which it is mounted, and the connections between said units are external to the means enclosing the combustion chambers and combustion-gas passes.
